UNITED STATES PATENT OFFICE

167,669

LIGHTING FIXTURE

Terence Frederic Peter Bell, Blackheath, Raymond Charles Kember, Croydon, and Leslie Thomas Anderson, Bromley, England, assignors to Thorn Electrical Industries Limited, London, England, a company of Great Britain

Application March 25, 1952, Serial No. 19,050
In Great Britain September 29, 1951

Term of patent 14 years

(Cl. D48—23)

To all whom it may concern:

Be it known that we, Terence Frederic Peter Bell, a subject of the Queen of Great Britain and resident of Blackheath, in the county of London, England, Raymond Charles Kember, a subject of the Queen of Great Britain and resident of Croydon, in the county of Surrey, England, and Leslie Thomas Anderson, a subject of the Queen of Great Britain and resident of Bromley, in the county of Kent, England, have invented a new, original, and ornamental Design for a Lighting Fixture, of which the following is a specification, reference being had to the accompanying drawing, forming part thereof.

Figure 1 is a bottom perspective view of a lighting fixture, showing our new design.

Figure 2 is a top perspective view thereof.

Figure 3 is an end elevational view thereof.
Figure 4 is a bottom plan view thereof.

We claim:

The ornamental design for a lighting fixture, as shown.

TERENCE FREDERIC PETER BELL.
RAYMOND CHARLES KEMBER.
LESLIE THOMAS ANDERSON.
